UNITED STATES PATENT OFFICE.

JACOB A. HYLE, OF PHILADELPHIA, PENNSYLVANIA.

COMBINED TIE PLATE AND RAIL ANTICREEPER.

Application filed March 19, 1923. Serial No. 626,024.

To all whom it may concern:

Be it known that I, JACOB A. HYLE, citizen of the United States, residing at Philadelphia, in the county of Philadelphia and State of Pennsylvania, have invented certain new and useful Improvements in Combined Tie Plates and Rail Anticreepers, of which the following is a specification.

This invention relates to a novel anti-creeper tie plate and is especially designed for the purposes of successfully preventing the creeping and spreading of the rails upon a railway track, as well as to retain the track rails in their proper alignment, and to insure a substantially perfect gauge being retained on both sides of the rail under any and all conditions.

The prime object of the invention is to provide a novel, simple, durable, economical, meritorious and thoroughly efficient combined tie plate and anti-creeper for the track rails of steam and other railway road beds.

Another object of the invention is to provide a tie plate for receiving the track rails, the plate being provided with novel locking means for engaging the rails, said locking means including balls which tend to move in tighter locking engagement with the base portion of the rails during vibration of said rails.

Another object of the invention is to so construct my improved tie plate, that the locking means will be prevented from moving out of engagement with the base of the track rail under all conditions.

A further object of the invention is the provision of a railway tie plate which can be rigidly secured to the usual cross tie, and which embodies a plurality of yielding lugs adapted to overlap the upper surface of the track rail base, the inner surface of each lug being formed with means for the reception and retention of the automatically movable locking means.

The foregoing and such other objects as may appear from the ensuing description are accomplished by the construction, arrangement, location and combination of the parts hereinafter more fully described, illustrated in the accompanying drawings, and particularly pointed out in the claims appended hereto, it being understood that slight changes in the precise proportions and minor details of construction may be resorted to without departing from the spirit or

sacrificing any of the advantages of the invention.

In the accompanying drawings forming a part of this specification, it will be seen that:

Figure 1 is a plan of the improved plate embodying my invention in its normal position beneath a railroad rail, showing the rail broken away and the locking means in dotted lines.

Figure 2 is a plan showing the position of the tie plate with respect to the rail before being forced into its normal position.

Figure 3 is a transverse section taken in the plane of the dotted lines 3-3, Fig. 1, looking in the direction of the arrows, and showing the movable locking means embraced by one of the clamping lugs.

Figure 4 is a side elevation showing the plate detached from the rail.

Figure 5 is a plan showing a blank form of the plate, and showing the depressions formed in the upper face of the plate before the rail clamping lugs are formed.

Figure 6 is a cross-section taken in the plane of the dotted lines 6-6, Fig. 4, looking in the direction of the arrows.

Figure 7 is an enlarged cross-section through one of the clamping lugs taken in the plane of the dotted lines 7-7, Fig. 4, looking in the direction of the arrow and showing the movable locking means resting on the recessed portion of said lug, and

Figure 8 is a slightly enlarged section taken in the plane of the dotted lines 8-8, Fig. 3, showing the locking means in engagement with the recessed inner face of one of the clamping lugs and the upper surface of the base of the rail.

In the embodiment of my invention as illustrated the numeral 1 designates the metallic plate preferably formed from rolled steel of the desired quality and any suitable dimensions, with a smooth flat lower surface having a thickened central body portion 2, the upper surface being beveled or gradually tapered from its thickened portion to each outer end 3 thereof. Said plate is then heated to the proper degree and while in its heated state a suitable die is placed on the face of the plate near its diagonally opposite corners and by a single blow of a suitable power hammer or forging machine, the recesses or depressions 4 of substantially the shape shown in Fig. 5 are formed therein, suitable spike openings 5 are then punched

therethrough by the proper machine, and the plate is then cut through in the plane of the dotted lines shown in Fig. 5, after which the plate, in its heated condition, is placed in a suitable machine and the said cut portions of the plate are bent or turned upwardly and inwardly to form yielding lugs 5', adapted to tightly clamp the upper surface of the rail base 6, the outer surface of each lug 10 being formed with a strengthening rib 7, and the inner face of each lug having a recess or depression 4 formed therein with a substantially straight central portion 8, terminating at its outer end in semi-circular form 9, and at its inner end with a lateral extension at each side thereof which is gradually shallowed toward its outer ends, as clearly shown in Fig. 8, said depression forming a pocket for the reception of a plurality of case hardened steel movable balls 10, adapted to contact with the upper face of the base of the track rail for the purpose hereinafter described.

By reference to Fig. 2 it will be seen that 25 the plate is first placed beneath the rail 11 substantially into the position shown, after which by striking the outer edge 12 of said plate with a sledge or heavy hammer the lower beveled faces of the lugs will be 30 caused to yieldingly slide inwardly to overlap the upper surface of the rail base until the plate assumes its normal position beneath the base of the rail, as shown in Figs. 1 and 3, thereby rigidly and securely clamping 35 the plate to the rail base, after which the steel locking and wedging balls, preferably three of said balls, are inserted into the outer end of the pocket formed by the recess or depression in each of the lugs, which 40 balls assume substantially the position shown in Figs. 1 and 7, and rest in contact with the rail base. In removing the plate from the track rail after the fastening spikes shall have been withdrawn it is simply necessary to turn the rail over, and if necessary 45 tap said rail or plate with a hammer and the steel balls will drop out of the pocket, then by striking the edge 13 of the plate with a sledge or heavy hammer the plate may be 50 easily detached.

It will be readily perceived that since the lateral extensions of each recess or depression formed in the inner face of each overlapping lug are shallowed gradually from 55 its central portion outwardly, when the steel locking balls are placed within the lug and caused to assume the position shown, the forward or backward movement of the rail will automatically cause a slight rolling or 60 turning movement of one of the balls onto the shallow surface thereby causing the ball to become tightly wedged against the rail base, thus successfully preventing any creeping 65 of the rail, at the same time allowing sufficient movement to permit the wave mo-

tion of the rail usually caused by heavy rolling stock passing over the track rails.

While I have shown three steel locking and wedging balls, it will be obvious that only one or two of these balls may be utilized 70 for effecting the desired purpose, and that the said locking means will serve to make it practically impossible for the rails to creep either way when employed in connection with a single or double track having traffic 75 in one or two directions.

By my novel construction and arrangement of combined tie plate and rail anti-creepers it will be evident, that a comparatively economical product is formed, which 80 is adapted to effectually serve to prevent the accidental spreading of the rails; to insure a perfect gauge and alignment of the rails on each side thereof at all times; that a smaller percentage of these plates will be 85 required to each rail than those usually employed, thereby creating a considerable saving per mile of road bed, and efficiently prevents the anti-creeping of the track rails.

It will be understood that as the plate is being forced into its normal position beneath the base of the rail the overlapping lugs made from the proper quality of steel are so formed that they will spring or yield gradually as they are caused to slide upon the inclined upper surface of the rail base, thereby causing the inward portion of each lug to grip the rail with more intensity when it is caused to assume its final and proper position beneath the base of the rail. 95

Having thus described my invention what I claim and desire to secure by Letters Patent is:—

1. A track-rail tie plate of the character described, comprising a rolled steel plate 105 formed with a lug disposed at each of two diagonally opposite corners, each lug overlapping and clamping the upper surface of the rail base, and each of said lugs having a recess formed in its inner face for the reception of locking means.

2. A track-rail tie plate of the character described formed of a single piece of steel 115 formed with a lug disposed at each of two diagonally opposite corners adapted to overlap and clamp the upper surface of the rail base, each of said lugs being formed with a recess in its inner face for the reception of steel ball locking and wedging means.

3. A track rail tie plate of the character described composed of a single piece of steel 120 having a plurality of lugs adapted to overlap the upper surface of the rail base, each of said lugs being formed with a pocket in its inner face for the reception of steel ball locking means.

4. A track-rail tie plate of the character described formed of a single piece of steel 125 formed with a lug disposed at each of two diagonally opposite corners, each lug yield-

ingly clamping and overlapping the upper surface of the rail base, each of said lugs being formed with a pocket in its inner face for the reception of steel ball locking means 5 adapted to contact with said upper surface.

5. A track-rail tie plate of the character described formed of a single piece of steel formed with a lug disposed at each of two diagonally opposite corners, each lug adapted to overlap and tightly clamp the upper surface of the rail base, each of said lugs being provided with a recess formed in its inner face, and steel ball locking means fitted into said recess in contact with said 15 upper surface.

6. A track rail tie plate of the character described formed of a single piece of rolled steel having a plurality of yielding lugs overlapping and tightly gripping the upper 20 surface of the rail base, each of said lugs being provided with a pocket formed in its inner face, and a plurality of locking and wedging balls fitted into said pocket in contact with the said upper surface.

25 7. A track rail tie plate of the character described formed of a single piece of rolled steel having a plurality of integral yielding lugs adopted to overlap and tightly clamp

the upper surface of the rail base, each lug having a recess formed in its inner face, and a plurality of case hardened steel balls fitted 30 into the said recess in contact with said upper surface.

8. A track rail tie plate of the character described formed of a single piece of steel 35 having a yielding lug adapted to overlap the upper surface of the rail base, said lug having a recess formed in its inner face, and automatically operated locking and wedging means fitted in said pocket in contact with 40 said upper surface.

9. A track rail tie plate of the character described formed of a single piece of metal having a thickened body portion and beveled end portions, a plurality of tapered overlapping yielding lugs adapted to tightly clamp the upper surface of the rail base, each of said lugs having a recess formed in its inner face and a central strengthening rib 45 on its outer face, and a plurality of steel 50 balls serving as locking and wedging means loosely fitted within said recess, said locking and wedging means being automatically operated by the movement of the rail.

JACOB A. HYLE.
